UNITED STATES PATENT OFFICE.

EDWARD ERICKSON, OF BEVERLY, MASSACHUSETTS, ASSIGNOR TO UNITED SHOE MACHINERY COMPANY, OF PATERSON, NEW JERSEY, A CORPORATION OF NEW JERSEY.

LEATHER-SKIVING MACHINE.

1,162,344.

Specification of Letters Patent. Patented Nov. 30, 1915.

Application filed March 20, 1914. Serial No. 825,956.

To all whom it may concern:

Be it known that I, EDWARD ERICKSON, a citizen of the United States, residing at Beverly, in the county of Essex and State 5 of Massachusetts, have invented certain new and useful Improvements in Leather-Skiving Machines; and I do hereby declare the following to be a full, clear, and exact description of the invention, such as will enable others skilled in the art to which it 10 appertains to make and use the same.

The present invention relates to leather skiving machines, and more particularly to feeding mechanism for machines for skiving 15 box toes and counters for boots and shoes.

The invention is designed primarily as an improvement on the feeding mechanism of the leather skiving machine disclosed in 20 the patent to Jacob R. Scott, No. 969,987, dated September 13, 1910. Heretofore difficulty has been experienced in machines provided with blank feeding mechanism like that disclosed in the Scott patent in properly 25 feeding the first or lowermost blank when the feeding mechanism is started in operation, with the result that the blank may be mutilated or the machine stopped or parts thereof damaged or broken.

30 The object of the present invention is to avoid this objection and to render the feeding mechanism certain in operation and capable of feeding the first or lowermost blank without liability of damage to the blank or to the machine.

With these objects in view, the present invention consists of the devices and combinations of devices hereinafter described and more particularly defined in the claims.

40 In the accompanying drawings which illustrate what is now considered the preferred form of the present invention as embodied in the machine of the Scott patent above referred to, Figure 1 is a vertical side 45 sectional view of so much of the Scott machine as is necessary to an understanding of the present invention, showing the feed slide and its actuating mechanism; Fig. 2 is a top plan; and Fig. 3 a side elevation, 50 both enlarged, of the member or link for actuating the feed slide.

55 In the machine illustrated in the drawings the die roller indicated at 1 mounted upon the shaft 2 is provided with a die cavity 3, as is customary in this type of machine.

A pressure device or roll 4 mounted upon the shaft 5 acts to force the blank into the die cavity and cooperates with the die roll 6 mounted in fixed position at the rear of 60 the machine. The blanks are supported in a vertical pile in the magazine or hopper 8, the lowermost blank resting upon the table 9 and being fed to the pressure and die rolls through the passageway 10 by means 65 of the feeding fingers 11 carried by the feed slide 12. Mounted in lugs 13 extending downwardly from the lower portion of the feed slide is the stud or pin 14 by which the slide is given its feeding and its return movements. The parts thus far described are identical with those disclosed in the 70 Scott patent above referred to.

The actuating mechanism for the feed slide comprises an oscillating shaft 15 upon 75 which is secured the arm 16. To the upper end of this arm is pivoted the link 17 which is cut away or recessed in its upper surface as at 18 for a purpose shortly to be described, and is provided near its free end 80 with an upstanding shoulder or abutment 19 for engaging the pin 14 and causing the feed slide to make its feeding stroke. The feed slide is given its return or idle stroke by means of a latch 20 pivoted at 21 on the 85 link 17 and normally held in raised position by the compression spring 22. The link 17 is also provided in its lower portion with a cam groove 23 to receive a cam roll 24 carried upon the pivoted arm 25. The 90 lever 25 carrying the roll 24 may be lowered and raised by means of the connection 26, lever 28, and rod 29, extending to suitable treadle mechanism, such, for example, as that shown in the Scott patent above referred to, producing a corresponding movement in the link 17 for the purposes of stopping and starting the feed slide. The link 95 is maintained in its raised or normal position by means of suitable locking devices 100 for the treadle mechanism as illustrated in said patent.

It is often desirable in machines of this character to stop the feed slide momentarily for the purpose of replenishing the supply 105 of blanks in the hopper or magazine, or for some other reason, yet without stopping the movement of other parts of the machine, including the actuating mechanism for the feed slide. In order to insure proper feed- 110

ing of the first or lowermost blank when the feed slide is again started in operation, it is essential that the first feeding movement of the slide be a full and not a partial movement, and preferably this is accomplished by causing the feed slide to come to rest at the end or limit of its feeding movement so that when started again in operation it will first make its idle stroke and then a full feeding stroke. To insure the feed slide stopping in its extreme inward position the shoulder or abutment 19 on the link is extended to such a height that even when the lever 25 and cam roll 24 are lowered to disconnect the link 17 from the feed slide, the abutment will still be in position to engage the pin 14 to cause the feed slide to make its feeding movement. By this lowering of the feed slide, however, the latch 20 will be withdrawn from engagement with the pin 14 so that on the return or idle stroke of the link 17 the feed slide will be left in its inward position where it will remain unaffected by the continued movements of its actuating mechanism.

When the lever 25 and roll 24 are raised, the latch 20 is brought to a position to engage the pin 14 (the position of which is shown in dotted outline in Fig. 1) as the link approaches the limit of its inward or feeding movement, and will be forced down against the action of spring 22 until at the end of the inward or feeding movement of the link, the latch rises and engages the inner face of the pin 14, whereupon the feed slide is again set in operation, beginning with an idle or return stroke. Inasmuch as the lever 25 is raised by treadle mechanism under the control of the operator, the position of the link 17 at such time in its feeding or return movements is uncertain, depending wholly upon the particular point or time in the cycle of operation of the feed slide actuating mechanism that the treadle 45 is depressed by the operator.

In the construction of links heretofore employed it was necessary for the operator to apply and maintain pressure upon the treadle for varying portions of the cycle of operation of the feed slide actuating mechanism before the link could be brought into its final operative position. Furthermore, owing to the fact that the upper face or edge of the link was inclined, there was liability 55 of forcing the feed slide a greater or less distance in the direction of its idle movement when the top of the link was brought into engagement with the pin carried by the feed slide, with the result that when the pin 60 was engaged by the abutment on the link on its inward or feeding movement, the slide would be given a partial feeding stroke, and a corresponding movement to the lowermost blank on account of the frictional contact 65 of the latter with the feeding fingers. The

presentation of a blank to the die roll under such conditions would be out of time with relation to the position or movement of the die cavity and as a result the blank would be spoiled and the machine stopped in operation or some of its parts damaged or broken.

In the present invention on account of the cutting away of the upper surface of the link and the provision of a pivoted latch, 75 the link may be immediately raised to its normal or operative position irrespective of the relative position of link and feed slide in the line of the feed, and will thereafter automatically become operative to set the 80 feed slide in regular operation when the link reaches substantially the end of its feeding movement. It is thus impossible for the feed slide to be given a partial work feeding stroke when first set in operation, 85 and damage to the blank or machine or stoppage of the machine is thus avoided.

While the present invention has been described as embodied in the specific construction illustrated in the drawings, it is to be 90 understood that it is not limited thereto, as it is capable of embodiment in many other forms and constructions.

Having thus described the present invention, what is claimed is:

1. A skiving machine, having, in combination, skiving mechanism and blank feeding mechanism, including a feed slide, an actuating member for moving the feed slide in both directions, devices for rendering said member operative, said devices comprising means arranged to be actuated by the operator irrespective of the relative position of the feed slide and member, and mechanism automatically becoming operative 105 thereafter when the member and slide are in predetermined relative position, substantially as described.

2. A skiving machine, having, in combination, skiving mechanism and blank feeding mechanism, including a feed slide, an actuating member for the feed slide movable into normal position irrespective of the relative position of member and slide, said member being provided with means for 110 actuating the feed slide in one direction when both in and out of normal position, and with means for actuating the feed slide in the opposite direction when in normal position only, and means for moving the 115 actuating member into and out of normal position, substantially as described.

3. A skiving machine, having, in combination, skiving mechanism and blank feeding mechanism, including a feed slide, a lever, a link pivoted at one end to said lever, the free end of the link being movable toward and from the feed slide and being provided with an abutment for actuating the feed slide in one direction when the free 130

end of the link is both in its nearer and also in its more distant positions relative to the feed slide, a latch pivoted upon the feed slide for actuating the feed slide in the opposite direction only when the free end of the lever is in its nearer position relative to the feed slide, and means for moving the free end of the actuating lever toward and from the feed slide, substantially as described.

4. A skiving machine, having, in combination, skiving mechanism and blank feeding mechanism including a feed slide provided with a contact piece supported beneath the same for actuating the slide in both directions, an oscillating lever, a link pivoted at one end to the lever and provided at its free end with a rigid abutment adapted to engage the back face of the contact piece on the feed slide to cause the slide to make its blank feeding stroke, a pivoted latch carried by the feed slide for engaging the front of said contact piece to cause the feed slide to make its return stroke, and

means for moving the free end of the link toward and from the feed slide to bring the latch into and move it out of position to engage the contact piece, substantially as described.

5. A skiving machine, having, in combination, skiving mechanism, blank feeding mechanism adapted to be thrown into operation by the operator, and devices for preventing the feeding mechanism from being started in operation except at a predetermined point in the cycle of operation of the machine, substantially as described.

6. A skiving machine, having, in combination, skiving mechanism, a feed slide, and actuating devices therefor including means for preventing said devices from giving the feed slide a shortened initial feeding movement, substantially as described.

EDWARD ERICKSON.
